UNITED STATES PATENT OFFICE.

JOHN N. LEONARD, OF ROCKVILLE, CONNECTICUT.

DESIGN FOR A SAMPLE-CASE FOR THREAD AND SEWING-SILK.

Specification forming part of Design No. 5,443, dated December 19, 1871.

To all whom it may concern:

Be it known that I, JOHN N. LEONARD, of Rockville, county of Tolland and State of Connecticut, have invented or discovered a new and useful Improvement in Design for Sample-Case for Sewing Thread or Silk; and to enable others skilled in the art to make and use the same I will proceed to describe, referring to the drawing, in which the same letters indicate like parts in each of the figures.

In the accompanying photographic view is shown a new and improved design for a sample-case for thread or sewing-silk, the sides *a a* and division-plate *b* of which are recessed or rabbeted to receive the heads of the spools, which are in-

troduced into the case in their proper order at one end of the case, and corresponding to the number imprinted on the edge of the sides and division, and when filled the end *d* is secured to the ends of the sides and division by screws *d'*. *f* is a hinged lid of the case, upon the inside of which are printed the quality, color, &c., each having its number corresponding with the number on the margin of the case.

What I claim is the design, substantially as shown and set forth.

JOHN N. LEONARD.
